Primary Examiner — Karen S Acker*Assistant Examiner* — Jonathan E Fiencke(74) *Attorney, Agent, or Firm* — STIP Law Group, LLC(57) **CLAIM**

The ornamental design for a drinking water supply for pets, as shown and described.

DESCRIPTION

FIG. 1 is a perspective view of the drinking water supply for pets, showing the present design.

FIG. 2 is a front view thereof.

FIG. 3 is a rear view thereof.

FIG. 4 is a left side view thereof.

FIG. 5 is a right side view thereof.

FIG. 6 is a top view of thereof; and,

FIG. 7 is a bottom view of thereof.

The broken lines and areas within depict portions of the drinking water supply for pets that form no part of the claimed design.
